UNITED STATES PATENT OFFICE.

JOHN J. RENCHARD, OF DETROIT, MICHIGAN.

OIL-CUP.

SPECIFICATION forming part of Letters Patent No. 278,742, dated June 5, 1883.

Application filed September 4, 1882. (No model.)

To all whom it may concern:

Be it known that I, JOHN J. RENCHARD, a citizen of the United States, residing at Detroit, in the county of Wayne and State of Michigan, 5 have invented certain new and useful Improvements in Oil-Cups for the Journal-Boxes of Crank-Pins, Eccentrics, and Cross-Heads of Engines and other Machinery; and I do hereby declare the following to be a full, clear, and 10 exact description of the invention, such as will enable others skilled in the art to which it appertains to make and use the same, reference being had to the accompanying drawings, and to letters or figures of reference marked there- 15 on, which form a part of this specification.

The object of my invention is to provide an oil-cup for eccentric cross-heads and crank-pins of engines and other machinery, which, while the machine is in motion, has a positive automatic feed, and when the machinery is at rest 20 cuts off the escape of oil.

The construction and operation of my invention is further explained by reference to the accompanying drawings, in which—

25 Figure 1 represents a vertical section. Fig. 2 is a detail showing a vertical section of the central connecting-stem, drawn at right angles to that shown in Fig. 1. Fig. 3 represents a detail, showing a plan view of the connecting- 30 tube.

Like parts are represented by the same reference-letters throughout the several views.

35 A is the body of the oil-cup, which is preferably made of glass, the ends of which are closed by the metallic cap B and coupling-stem C, the joints between the cup and the metal being packed by corks or other elastic packing, *aa*. The cap B and stem C are drawn toward each other and secured firmly against the ends 40 of the glass body by the connecting stem or link D.

E is a stopper which closes the mouth of the oil-cup.

45 F is a sleeve which is cast in the same piece with the cap B. Said sleeve is provided with a female screw for the reception of the screw on the stopper and the screw on the connecting-link, as shown. When the stopper is removed the oil is poured into said sleeve, from 50 which it escapes through the openings G into the cup A. The oil is discharged from the cup to the crank-pin or other journal-boxes

by the action of the plunger H, which plunger has a reciprocatory upward and downward movement, caused by the action of the pendulum I. The pendulum I is pivoted to the side of the stem D in the box J; the lower or pivoted end of said pendulum, being formed at right angles to the upright part thereof, as shown, is caused to perform a partial revolution as the pendulum oscillates, whereby the rod K, which is inserted through the horizontal end of said pendulum, is caused to rise and fall from the position shown in Fig. 2 to that indicated by dotted lines. The rod K passes 60 through a loosely-fitting opening in the plunger H, and as it moves upward and downward carries the plunger with it. The pendulum is caused to oscillate, as mentioned, to and from the positions indicated in Fig. 2 by the motion of the crank-pin or eccentric. The upward and downward movement of the plunger, and consequently the movement of the pendulum, is governed by the adjusting-screw L, said plunger being adapted to move downward until its lower end strikes the coupling-joint C, and to move upward until its upper end strikes the screw L. Thus the motion of the plunger is increased by raising the screw and decreased by lowering it, whereby the quantity of oil discharged by each movement is regulated. An oil-space, O, is left in the coupling D, around the plunger, for the reception of oil, which oil enters said space through the openings M. The lower end of said plunger is enlarged, thus 75 forming a piston, N, which is fitted to the lower end of said stem D, and when drawn upward prevents the escape of oil from said stem. When said plunger is moved downward, said piston or enlarged end is brought below the 80 orifice of said stem D and a small quantity of oil escapes from said stem into the recess O, from whence it escapes around the angular or loosely-fitting rod P into the journal-box of the cross-head. The dimensions of the rod P 85 are such that the oil in said recess O is prevented from escaping, except slowly of its own gravity, but is discharged therefrom after said chamber is filled by pressure from the lower end of said plunger or piston as it moves downward into said chamber.

90 It is obvious that, if desired, the pendulum may be suspended below its pivotal bearings, when the oscillating movement will be sub- 95 100

stantially the same; but the form shown is, however, preferred.

Having thus described my invention, what I claim as new, and desire to secure by Letters 5 Patent, is—

In an oil-cup for wrist-pins, eccentrics, &c., the combination of cup A, cap B, coupling-stem C, connecting-stem D, pendulum I, arm K, plunger H, and adjusting-screw L, said cap B 10 being provided with an opening for stopper E, through which the cup is filled and the screw L adjusted, said screw L and plunger H being arranged within said coupling D in such a manner that with each alternate movement of 15 the pendulum I said plunger is brought in contact with the adjusting-screw, said screw being

adapted to regulate the upward and downward movement of said plunger, whereby the escape of oil with each alternate movement of said pendulum is governed, said coupling C being 20 provided with oil-space O, said plunger H being provided with piston N, as adapted to eject the oil from said space O with each downward movement of said plunger, all substantially as and for the purpose specified. 25

In testimony whereof I affix my signature in presence of two witnesses.

JOHN J. RENCHARD.
